FARNUM E. DORSEY, OF ROCHESTER, NEW YORK, ASSIGNOR TO NORTH EAST APPLIANCES INC., OF ROCHESTER, NEW YORK, A CORPORATION OF NEW YORK.

POWER MECHANISM.

Application filed July 31, 1925. Serial No. 47,379.

This invention relates to power mechanism for use in connection with typewriters or similar machines. More particularly, it is adapted for applying power to the operation of case-shifting, or to any similar operation in which it is desirable that movement of a manually operable member or key in one direction shall result in a corresponding movement of the carriage, or other part 10 which is to be actuated, while the release or return of the key to normal position causes a return of said part to its normal position.

The invention will be described particularly in its application to the case-shift mechanism of a typewriter, although it will be evident that it may also be applied to such parts as a tabular stop, or to parts having analogous functions in machines other than typewriters.

One object of the invention is to produce mechanism, for the purpose set forth, which shall be simple, reliable and rapid in operation. Another object of the invention is to provide such mechanism in a form such that its members may be to a large extent interchangeable with the members of power mechanism for operating the type-bars of the same machine. Another, and particular object of the invention is to produce a mechanism in which the work incidental to the performance of the case-shift, or analogous function, is performed, so far as possible, by the power mechanism and not by the key which controls this operation, so that the key may be operated with no more resistance than is encountered in operating the keys by which the type-bars are controlled.

To the foregoing ends, the invention consists in the power mechanism hereinafter described, as it is defined in the annexed claims.

In the accompanying drawings, Fig. 1 is a partly sectional side-elevation of parts of a typewriter including power mechanism embodying the present invention, with the parts shown on a reduced scale. Fig. 2 is a side-elevation, on a larger scale, of a portion of the mechanism shown in Fig. 1, including particularly the rocker and the pull-member thereof. Fig. 3 is a front-elevation of the parts shown in Fig. 2, taken partly in section on the line 3-3 in Fig. 2. Fig. 4 is a side-elevation of the cam-unit of the power mechanism; and Fig. 5 is a rear-elevation of the same. Fig. 6 is an elevation of the cam,

showing the side opposite to that shown in Fig. 4.

The invention is illustrated as embodied in a typewriter of well-known general form, having at its upper part a carriage 10, which supports the usual platen-roller. This carriage has the usual rollers 11 through which it is supported, in part, by a horizontal transverse rail 12.

The power mechanism comprises a roller 13 which is journalled transversely near the bottom of the frame of the machine, and which is rotated constantly, in the direction of the arrow in Fig. 1, by power from any suitable source, such for instance as an electric motor (not shown). This roller is preferably covered with rubber or other yielding and frictional material.

The roller serves to actuate, under the control of a suitable key, a pivotally mounted assembly which may be called the cam-unit. This assembly comprises a cam 14, free to rotate on a pivot 15, which is supported between two depending arms 16. These arms are integral with a horizontal arm 17; the arms 16 and 17 constituting a bifurcated bell-crank cam-lever provided with a pivot 18 which turns in a suitable bearing on the frame of the machine. The cam has two similar lobes, each of which has a toothed surface that has a rolling engagement with the power-roller, while the intermediate or reentrant parts of the cam are of minimum diameter. A normal inactive position of the cam is shown in the drawings, the cam at this time presenting one of its reentrant portions toward the roller. Engagement of the cam with the roller may be caused by a slight clockwise rotation of the cam upon its pivot 15. Such rotation is produced by means of an arm 19, which swings on a pivot 20 between the two arms 16. The cam is provided with two diametrically opposite pins 22 projecting laterally from its web, and a spring 21, coiled about the hub of the spring-arm 19, causes the arm to press against whichever of these pins is in the lower position, as shown in Fig. 4.

Rotation of the cam by the spring-arm is normally prevented by a stop-lever 23, which is also mounted to swing about the pivot 20. Near its lower end the stop-lever is provided with a laterally extending stop-

lug 24 which cooperates with two detents 25 and 26 on the cam. The detent 25 extends directly from the flange of the cam, as shown in Fig. 5, while the detent 26, although formed from the metal at the corresponding opposite part of the cam, is offset inwardly, as shown in Fig. 6, so as to be near the axis of rotation of the cam.

The upper arm 27 of the stop-lever has a laterally bent extremity 28, which is received by the forked extremity 29 of a key-lever 30. This key-lever is pivoted at 31 on the frame of the typewriter, and it is provided, near its forward end, with a key 32, occupying the position of the ordinary shift-key of a typewriter. The forward end of the key-lever moves in a suitable guide and stop-member 33, and is normally held in raised position by a spring 34. In the normal position of the parts, as shown, the lower arm of the detent-lever is swung rearwardly, and the stop-lug 24 is engaged by the detent 25 on the cam, the cam being thus held against rotation. In this position of the parts, if the key 32 be depressed, the lower end of the detent-lever is swung forwardly so as to move the lug 24 out of the path of movement of the stop-lug 25. Thereupon, the spring-arm 19 turns the cam 30 enough to cause engagement with the power-roller, and such engagement causes rotation of the cam, with a resulting rocking movement of the cam-lever. After the cam has rotated so that the summit of its upper lobe 35 has engaged the roller, continued rotation of the cam permits the cam-lever to return to its original position, under the influence of a spring hereafter referred to. Since the stop-lever has been swung forwardly, the stop-lug 24 is now in position to be engaged by the detent 26 on the cam, and the cam is thus arrested at the end of a half-rotation, and remains out of engagement with the power-roller until the key 32 is released and 40 permitted to rise. In consequence of this rising movement the detent-lever is swung back to its original position, thus disengaging the stop-lug 26 and permitting the cam to make another operative engagement with the power-roller, and to cause another similar swinging movement of the cam lever.

From the foregoing description, it will be understood that the cam assembly operates once at each depression, and again at each 55 return movement, of the shift-key.

The cam-lever is connected, by an adjustable pull-rod 35, with a plate 36, which may be called the hook-plate. This plate lies alongside a pivotally movable member 37 in the form of a three armed lever, formed of sheet-metal. The member or "rocker" 37 is pivoted on a stud 38, projecting from a plate 51 which constitutes a part of the stationary framework of the machine. The 60 rocker is provided with two pins 39 and 40

on opposite sides of its pivotal point, and a guide-plate 41 is fixed on the outer ends of the pins and lies parallel with the rocker. The hook-member 36 is embraced loosely between the rocker and the guide-plate. 70

The hook-member has a large central opening which receives the pivot-stud 38 and the rocker-pins 39 and 40 and it is provided, on opposite sides of this opening, with hook-like shoulders or abutments 42. The space 75 between these abutments is such that when one of them is in engagement with one of the pins, the other pin may swing clear of the other abutment. Thus, the hook-member may be caused to engage the two rocker-pins 80 alternatively, according as it is swung to a forward or rearward position.

The rocker is provided, at its upper end, with a pin 43, and a pin 44 projects from the plate 51 above the pin 43. A coil-spring 45 85 is hooked at its ends around these two pins, and the form and relation of these parts are such that the spring resists swinging movement of the rocker in either direction, and acts to keep it in either its forward or rearward position, as the case may be, until it is moved therefrom by positive means. Two stop-pins 46 and 47, projecting from the plate 51, determine the forward and rearward positions of the rocker. The parts are 90 shown in opposite positions in Figs. 1 and 2.

A tension-spring 48 is attached, at its upper end, to the pin 43, while its lower end is attached to a lug 49 on the hook-member. This spring holds the hook-member normally in raised position, and performs the function of returning the cam-lever to its normal position after each operative movement thereof. The hook-member is provided with a stop-surface 50 which engages 100 the stud 38 and limits the upward movement of the hook-member, the parts being adjusted so that, when so arrested, the cam will have only the necessary clearance from the power-roller to prevent engagement therewith. 105

A link 52 is pivoted, at one end, on the pin 43 carried by the rocker, while the rear end of the link is pivoted on a pin 53 at the upper end of an arm 54. This arm is fixed 110 on a rock-shaft 55 which turns in bearings on the frame of the machine. A roller surrounding the pin 53 moves in an inclined slot in a lever 56, which is pivoted at 57 on the frame of the machine. The forward 115 end of the lever is pivoted to a push-rod 58 attached, at its upper end, to the rail 12. While the means just described serve to support the rail at only one point, it will be understood that the rock-shaft 55 may extend across the machine, and that the parts 54, 56 and 58, may be duplicated at both sides of the frame, so as to maintain the rail in horizontal position. 120

In Fig. 1 the mechanism is shown in the 130

position occupied by the parts when the carriage 10 is in its lower position. In this position of the parts the hook-member is engaged with the rock-pin 39, as shown in Fig. 1. If now the key 32 be depressed, the cam is caused to actuate the cam-lever as hereinbefore described, so as to pull the hook-member downwardly and then to permit the spring 48 to raise it again. This downward movement of the hook-member is transmitted, through the pin 39, to the rocker, causing the latter to swing to the rearward position shown in Fig. 2. Through the link 52, the arms 54 are swung rearwardly, causing the rollers carried thereby to raise the levers 56, the rods 58 and the rail 12, thus moving the carriage to upper-case position. So long as the shift-key is held down by the operator the spring 45 holds the parts 36, 52 etc. in the position shown in Fig. 2.

The movement of the rocker from forward to rearward position causes the line of pull of the spring 48 to be shifted from a position in front of the pivot-stud 38 to a position in the rear of this stud, and this spring acts, accordingly, not only to raise the hook-member, but also to swing it from its forward position, shown in Fig. 1, to its rearward position shown in Fig. 2. In this latter position the forward abutment on the hook-member is brought into line with the rocker-pin 40, while the rear abutment is moved rearwardly out of the path of movement of the pin 39. With the parts in this position, if the operator releases the shift-key and permits it to rise, thus causing a second actuation of the cam-lever, the resulting downward movement of the hook-member acts, through the pin 40, to swing the rocker back to its forward position, thus restoring the parts to the position of Fig. 1 and permitting the carriage to fall again to lower-case position.

The operation of the power mechanism is so rapid that the cam normally completes its half-rotation while the shift-key is still depressed, and before it can be released by the operator. If the shift-key be given a very rapid tap, however, the stop-lever may be permitted to return to its normal position after releasing the detent 25 and before engagement with the detent 26. The operation of the mechanism will not be deranged in this case, however, for the result will be merely a complete rotation of the cam without interruption, causing the carriage to be

lifted and instantly lowered again, with the parts again coming to rest in the normal position.

The key-lever 30 is shown as articulated with a crank-rod 59, through which it may be connected with the usual duplicate shift-key lever on the opposite side of the machine.

The invention claimed is:

1. In a typewriter or the like, the combination, with a part to be moved and a manually-operable key, of a rocking member pivotally mounted to rock into two alternative positions; connections, between said member and said part, for moving said part into two alternative positions as said member is moved from one to the other of its said positions; a spring, connected with said member, tending to resist its movement from either position; and power-actuated means, controlled by said key, constructed and arranged to swing the rocking member alternately in opposite directions upon successive operations of the power-actuated means.

2. In a typewriter or the like, the combination, with a part to be moved and a manually operable key, of power mechanism, for moving said part, comprising: a constantly moving power-member; a driven member co-operable with said power-member, normally disengaged therefrom, but operable, under control of said key, to engage and be moved by the power-member; and mechanism, interposed between said driven member and said part to be moved, constructed and arranged to cause successive similar movements of the driven member to produce successive opposite movements of said part.

3. In a typewriter or the like, the combination, with a part to be moved and a manually operable key, of a constantly rotary power-roller; a cam-lever; a cam journaled on said lever and having successive similar lobes; means, controlled by said key, for turning said cam into engagement with said roller and for arresting its rotation after the cooperation of each lobe with the roller, whereby successive similar swinging movements of the cam-lever are produced, said means being operative once when the key is depressed and again when the key is raised; and mechanism, interposed between the cam-lever and said part to be moved, for producing successive opposite movements of said part in consequence of successive similar movements of the cam-lever.

FARNUM F. DORSEY.
